EAR PHONE HEAD SET

Edward Charles Scanlon, 13 Richmond Ave.,
West Barrington, R.I.

Filed Feb. 23, 1965, Ser. No. 83,936

Term of patent 14 years

(Cl. D26—14)

FIG. 1

FIG. 2

FIG. 3

FIG. 4

FIG. 5

FIGURE 1 is a left side, top and front perspective view of an ear phone head set, showing my new design;

FIGURE 2 is a top plane view, to an enlarged scale;

FIGURE 3 is a left side elevational view to an enlarged scale;

FIGURE 4 is a right side elevational view to an enlarged scale; and

FIGURE 5 is a rear elevational view thereof.

Portions of the drawing figures have been omitted to indicate indeterminate length.

I claim:

The ornamental design for an ear phone head set, as shown and described.
